UNITED STATES PATENT OFFICE

162,236

AUTOMOBILE GRILLE BAR

David E. Scott, Detroit, Mich., assignor to Chrysler Corporation, Highland Park, Mich., a corporation of Delaware

Application March 18, 1950, Serial No. 8,629

Term of patent 7 years

(Cl. D14—18)

To all whom it may concern:

Be it known that I, David E. Scott, a citizen of the United States, residing in the city of Detroit, county of Wayne, and State of Michigan, have invented a new, original, and ornamental Design for an Automobile Grille Bar, of which the following is a specification, reference being had to the accompanying drawing, forming part thereof, in which:

Fig. 1 is a front elevational view of an automobile grille bar showing my new design;

Fig. 2 is a top plan view thereof; and

Figs. 3 and 4 are cross sectional views taken on the lines 3—3 and 4—4 respectively of Fig. 1.

The characteristic features of my design reside in the portions shown by means of full lines in the drawing.

I claim:

The ornamental design for an automobile grille bar substantially as shown and described.

DAVID E. SCOTT.
